No. 14,983

Apr. 29, 1884

UNITED STATES PATENT OFFICE.

GEORGE E. NYE, OF BRISTOL, PENNSYLVANIA, ASSIGNOR OF ONE-HALF TO
EDWARD TREDICK, OF SAME PLACE.

DESIGN FOR HOSIERY.

SPECIFICATION forming part of Design No. 14,983, dated April 29, 1884.

Application filed February 23, 1884. Term of patent 7 years.

To all whom it may concern:

Be it known that I, GEORGE E. NYE, of Bristol, Bucks county, Pennsylvania, have invented a new Design for Hosiery, of which the following is a specification.

The design is fully represented in the accompanying photograph. It embraces as distinguishing features wide vertical ribs, *a*, at the front, combined with narrower vertical ribs, *b*, at the rear of the stocking. There are also transverse ribs *c*, which are commonly made of different widths, as shown. It will be ob-

served that there are two series of these transverse ribs—one at the top and the other at the middle portion of the stocking. Those at the top are not essential, and may be omitted.

Having thus described my invention, what I claim is—

A design for hosiery, substantially as herein described and shown.

GEORGE E. NYE.

Witnesses:

EDWARD TREDICK,
JESSE O. THOMAS.
